INDIVIDUAL MAUSOLEUM

Benjamin F. Krehbiel, Wichita, Kans.

Application February 15, 1933, Serial No. 656,847

18 Claims. (Cl. 72—7)

This invention relates to an improvement in individual mausoleums. The objects of my invention are to provide an individual mausoleum having great strength and one that is water or moisture tight. A still further object is to provide an individual mausoleum having a vent, or a plurality of vents to admit the passage of gases or moisture or both out of the mausoleum, but will prevent the passage of such matter into the mausoleum. Another object of my invention is to provide a mausoleum of the character mentioned and in addition thereto to provide a disinfectant material within the mausoleum in such a place or places that all gases or moisture therein will be disinfected before they are permitted to pass out of the mausoleum. These and other objects will be more fully described as this description progresses.

Now referring to the drawings in which like reference characters represent the same part in the several figures, Fig. 1 is a longitudinal sectional view through my improved individual mausoleum, the assembly thereof being complete. Fig. 2 is a transverse sectional view of the complete assembly as seen from the line II—II in Fig. 1. Fig. 3 is a longitudinal sectional view of the box portion only, showing a modified form of construction in the lower portion of the box. Fig. 4 is a sectional view through the side wall of the box as seen from the line IV—IV in Fig. 3. Fig. 5 is an enlarged detail plan view of the construction and assembly of the sealing tray and strut bars at the top of the box. Fig. 6 is a plan view of the complete assembly. Fig. 7 is a plan view of the under side of the sealing lid. Fig. 8 is a plan view of my improved individual mausoleum having the monumental cover and the sealing lid removed and a portion of the box broken away for convenience of illustration. Fig. 9 is a plan view of my improved individual mausoleum having the monumental cover, sealing lid, strut bars and sealing tray removed and a part of the subfloor broken away for convenience of illustration. Fig. 10 is an enlarged sectional view of a valve for venting gases and moisture out of the mausoleum. Fig. 11 is a plan view of Fig. 10. Fig. 12 is a modified form of a valve or trap which may be used in lieu of that shown in Figs. 10 and 11. Fig. 12A is still another type of vent that may be employed instead of that shown in Figs. 10 or 12. Fig. 13 is an enlarged sectional view of the assembly of the several parts at the top of the box, the section being taken through the joint at any one of the strut bars. Figs. 14 and 15 are details showing a method of tighten-

ing the reinforcing bars in the concrete after the concrete has shrunk in the process of curing. Fig. 16 is a face view of the right hand side of Fig. 15.

In the drawings is shown my improved individual mausoleum having a box or vault portion A, consisting of four walls 17, 18, 19 and 20 and a bottom 21. The upper portion of the walls 17, 18, 19 and 20 are rebated or provided with a shoulder 22 for the support of, and on which rests the sealing lid 23. At 24 are dove tail notches in the side walls 17 and 19 of the box or vault for a purpose which will be later explained. In the top edge of the walls is a sealing strip 25 which is preferably made of copper, or some rust resisting material. It will be noticed that the sealing strip 25 is imbedded in the concrete walls of the vault and projects thereabove, the reason of which will be later explained.

Along the inner corners of the vault where the floor joins the walls is shown a shoulder 26 with notches 27 therein to receive bars or concrete joist 28 on which rests the casket which is not shown. In Fig. 1 is shown a sub floor 29 which rests on the two concrete beams or joist 28 and 25 the edges of the sub-floor 29 between the joists 28 rest on the shoulder 26.

In Fig. 3 is shown a sub-floor slab 29a which rests on the joist 28 and the sides and opposite end of the slab rest on the shoulder 26 and the same construction exists in the opposite end of the vault. The reason for this construction and that described in the preceding paragraph will be later explained.

In some localities surrounding the cemeteries there is a growing complaint that the ground is becoming contaminated from the dead bodies etc., buried in the cemetery, therefore in my improved mausoleum I have provided a drain in the floor or bottom of my mausoleum vault and also a means of disinfecting any and all liquids that may drain from the vault before they are permitted to leave the vault. These features are provided for as follows.

In Figs. 1, 2, 3, 9, 10 and 11 is shown a vent and disinfecting device for allowing the gases and moisture that may exist in the vault to pass out while in Figs. 12 and 12a is shown two types of valves or vents that would give satisfactory results. The drain or valve is placed in the floor of the vault and the floor slopes from its outer extremities to the drain as shown. On the floor of the vault at 30 is a tubular porous material which functions as a filter and around which is placed any desired disinfecting material 31 such

as chloride of lime etc. In the floor of the vault and on the center axis of the filter 30 is the drain or valve which as shown in Figs. 1, 2, 3, 9 and in enlarged detail in Fig. 10 comprises an enclosure casing 32 with a valve 33 in the top thereof and which is covered with a fine screen element 34 which extends from the top of the case 32 through the concrete and into the open space within the filter 30. At 35 is a hole in the concrete which extends from the top of the case 32 through the concrete and into the open space within the filter 30. At 35' is a hole in the concrete which extends to the bottom of the casing 32, there being openings in the bottom of the casing that open into the hole 35'. Within the casing 32 is a vertical spindle which is rigidly mounted on the bottom of the casing 32 and which supports a float 36 which carries a valve 37 which when the float is raised seats in the valve seat 33 and closes the passage from the exterior to the interior of the vault so no water may enter the vault from the outside. Any moisture from the inside of the vault will drain down the inclined floor through the disinfectant 31 and filter 30 and out through the valve mechanism into the outside ground, while any gases in the vault would be forced to travel under the sub-floor and over the disinfectant and then pass out through the valve the same as the moisture did.

Attention is drawn to the fact that the sub-floor 29 or 29a is always positioned over the filter 30 regardless of whether it is in the center of the vault as shown in Fig. 1 or whether it is in one end of the vault as shown in Fig. 3, this is done to prevent anything from dropping into the filter from above.

In Fig. 12 is shown a form of a valve that may be substituted for that shown in Fig. 10. This valve merely amounts to a trap having a ball 38 positioned on a seat in the trap to prevent flow of any material into the vault from the outside. In Fig. 12A is shown a type of drain which is merely a hole 38' through the floor slab and having a screen 38x therein to prevent anything of any size from passing into the vault. It will be understood that the same filter and disinfectant arrangement will be employed as is employed in Figs. 10, 11 and 12. These valves and numerous others may be employed with satisfactory results, the main idea being to provide a valve which will permit the passage of gases and liquids out of the vault and prevent their entering the vault.

The type of vault shown in Fig. 1, which has the drain in the center of the floor of the vault would be preferred when using a burial lot having a level surface while if a burial lot on a hillside were to be used and the vault as shown in Fig. 3 were to be set in a sloping position, the vault with the drain in one end would be preferable to use. The vault would be set so that the drain would be in the low end.

The vault is provided with a sealing tray 39 which fits within the walls of the vault and is provided with outwardly projecting lugs 40 which are adapted to enter and be received into the dove tail notches 24 and be supported on the shoulder at the bottom of the dove tail notch and thereby support the sealing tray 39 in its proper position within the vault. The sealing tray 39 is ribbed around its outer edges and also crossways from lug to lug 40 as a reinforcing element for the tray. If desired, the sealing tray 39 can be sealed to the walls of the vault by slushing cement between the bevel portion 39x

of the sealing tray and the walls of the vault.

Over each of the ribs between the lugs 40 and resting thereon is placed a strut bar 41 having bifurcated or hallowed ends so that the bifurcations 42 straddle the dovetail notches 24 and the entire bar 41 fits between the walls 17 and 19 of the vault and reaches in depth from the top of the ribs on sealing tray to the shoulder 22 on the walls 17 and 19. Attention is now drawn to the fact that the assembly just described has left an opening or hollow space above the lugs 40 and bounded by the dovetail notches 24 and the bifurcated ends 42 of the strut bars 41. This opening, when the vault is prepared for final sealing, is filled with concrete 43 which when set 15 will lock the sealing slab 39 and strut bars 41 in place between the walls of the vault. At 23 is a sealing cover, the under side of which is ribbed as shown at 45 in Fig. 7 in order to strengthen the cover. In the sealing cover 23 are 20 downwardly projecting bolts 44 which, when the sealing cover 23 is placed in position between the walls of the vault and resting on the shoulders 22, will be imbedded in the fresh cement 43 in the space between the bifurcations 42 and the walls 25 17 and 19 and when the cement 43 is set, the sealing cover is positively tied and permanently sealed to the vault.

It will be noticed that there is a dead air space between the sealing tray 39 and the sealing lid 30 23. There may be instances where it would be desirable or advisable to allow air circulation through this space and even provide a disinfectant material therein. This can be accomplished by making holes as indicated by the dotted circles 35 39' in the ends of the sealing tray 39 and placing the disinfecting material on top of the sealing tray 39 as indicated at 39a in Fig. 1.

It is customary to set graves or vaults in an east and west direction, and by setting my improved 40 vault in an east and west direction the following action takes place. When the sun rises in the east, the east end of the vault cover is heated first, thereby causing the air in the vault to rise in the east end of the vault, therefore it necessarily follows that the air will drop in the west end of the vault, it is obvious that this movement is nothing short of a complete movement or circulation of the entire air content of the vault. During this air circulation, any moisture in the vault will be evaporated into the air and absorbed 50 into the disinfectant and absorbent 39a. As the sun passes to the west, the west end of the vault cover is heated more than the east end and the air in the vault will circulate as previously described, except it circulates in the opposite direction.

Quite often it is desired to set these vaults in the cemetery lot some time before they are to be used, therefore it is desirable to seal the vault so it will not take moisture and yet it may be opened again at the time of interment. This is done by assembling the several parts in their proper position and omitting the cementing of the parts together. However a material such as putty may be placed in the groove 48 in the monumental cover of the vault and over the metallic tongue 25 and then placing the monumental cover 47 in its proper position on the vault thereby forming a temporary moisture proof 65 sealing of the vault until the time of interment. In the final assembling of the vault the sealing cover 23 and the upper edges of the vault walls are mopped with a heavy coat of water proofing, preferably hot asphalt, filling the space between 70 75

the walls of the vault and the outside edges of the sealing slab to form a water and air tight joint at that point. While the waterproofing is still hot, the vault is covered with a light weight felt 46 and thoroughly mopped down again with hot asphalt and the monumental cover 47 is placed on the vault, there being a groove 48 in the under side of the monumental cover 47 to receive the tongue or strip 25 to perfect a seal between 10 the walls and cover for the vault and the monumental cover 47.

On the monumental cover 47 is an inscription or name plate base 49 in which can be cast colored letters, name plates, lodge emblems, etc., 15 50, as an integral part of the base 49, and by the same process other emblems, etc., can be cast in the monumental cover as illustrated by the cross 50'.

In making an individual mausoleum of this 20 kind it is particularly desirable that it be permanently waterproof. In view of this fact the walls and bottom of my improved vault are poured and reinforced with wire mesh or steel rods and when set are water proofed with a heavy 25 coat of waterproofing 51 over which is placed a wire mesh 52 and a thick coating of cement 53' is sprayed thereon as a protection for the waterproofing.

It is well known that when concrete sets or is 30 cured that it shrinks to some extent and when this shrinkage takes place the steel in the concrete is under compression in the concrete and the concrete is in stress and as a result small 35 cracks will appear in the concrete and if there was a way to take up or shorten the steel, equal to the shrinkage, the cracks would not appear. In view of this I have provided the following described device and way to accomplish the shortening or taking up of the steel to allow for this 40 shrinkage and preventing the cracks from appearing in the concrete.

The reinforcing rods 53 are provided with a covering or coating such as a layer of paper or a thin coating of rubber or even a coating of oil 54 so that the concrete will not adhere to the steel 45 when the concrete is poured around it. One end of reinforcing rod 53 is enlarged or may have a large washer 55 riveted thereon as at 56 and the opposite end of the rod is threaded into a cylindrical piece 57 which is rotatably mounted in a cup like element 58 that is cast in the concrete 59. The outer end of the element 57 being provided with a hole 60 to receive a wrench with which the element 57 may be turned to take up 55 the extra length of the reinforcing rod as the concrete shrinks in the process of setting and curing, thereby placing the rod in tension and the concrete in compression as it should be.

While I have described the rod 53 as being taken up at one end it will be understood that a take up device as above described may be put on each end of the rod or there may be instances where it would be better to deform both ends of the rod and place a turn buckle in the middle of the rod.

Such modifications of my improved individual mausoleum and construction devices therein may be employed as lie within the scope of the appended claims without departing from the spirit 70 and intention of my invention.

Now having fully described my invention, what I claim as new and desire to secure by Letters Patent is:

1. In an individual mausoleum, a vault, said 75 vault having integral sides, ends and bottom, a

drain in said bottom and a protective sub-floor positioned over said drain, a sealing tray for said vault as a means of preventing moisture from dripping into said drain, without first passing through the disinfectant and filter block, said sealing tray being supported in the top portion of said vault, strut bars between the side walls of said vault and a sealing lid for said vault, means for supporting said sealing lid in said vault and means for rigidly and permanently holding 10 said sealing lid in position in said vault, a monumental cover for said vault and means in said vault to seal and hold said monumental cover on said vault.

2. In an individual mausoleum, a vault, said 15 vault having integral bottom, side and end walls, a shoulder on the inner side of said walls and adjacent the upper edges thereof, dove tail notches in the side walls, said notches extending below said shoulder, a sealing tray, said sealing 20 tray having outwardly extending lugs thereon, said sealing tray being adapted to fit between the walls of the vault with the lugs thereon resting on the bottom of the dove tail notches to support the sealing tray, strut bars, and a sealing lid for 25 said vault, said strut bars being positioned between the sealing tray and sealing lid, said strut bars having bifurcated ends so positioned that they straddle the dove tail notches to form an irregular shaped opening which may be filled with 30 concrete as a means of permanently locking the sealing tray and strut bars in said vault, said sealing lid having downwardly projecting elements so positioned that the sealing lid may be placed between the walls of the vault and rest 35 on the shoulders on said walls and the downward projecting elements on said sealing cover will enter into the fresh concrete between the bifurcated ends on the strut bars and the dove tail notches on the side of the vault so that when the 40 fresh concrete sets and hardens the sealing lid is positively and permanently sealed in position between the walls of the vault, a waterproof covering and sealing element for said sealing lid and upper edges of the walls of the vault and a monumental cover for said vault and means for sealing and holding said monumental cover on said vault to form the complete assembly of the 45 mausoleum.

3. In an individual mausoleum, said mausoleum having a concrete vault and covers therefor, said concrete having reinforcing rods therein, said rods being covered to prevent the adhesion of the concrete thereto, a head or deformation on one end of said rod and threaded means on 50 the other end of said rod to take up the length 55 thereof as and for the purpose set forth.

4. In an individual concrete mausoleum of the kind described, the concrete in said mausoleum being reinforced with wire mesh and steel rods, 60 said steel rods being deformed at one end to secure it from movement in the concrete, the opposite end of said rod being threaded into a nut that is housed so it may be turned after the concrete is set, said rod being treated between its ends to prevent the adhesion of the concrete thereto, substantially as shown and described and for the purpose set forth.

5. In an individual concrete mausoleum, said 70 mausoleum having a vault with integral sides and bottom which are covered with a waterproofing material and then overcoated with concrete as a protection for the water proofing, a sealing lid on said vault and a water proofing material placed over said sealing lid and upper edges of 75

the walls of said vault and joint between said walls and sealing lid to form a complete water proof membrane around all six sides of the vault, and a cover for said vault as a protection for the sealing lid and water proof membrane over the same.

6. In an individual mausoleum, the combination of a mausoleum having a vault and a sealing lid thereon and a continuous protected water proof membrane there around, a tongue in the upper edge of the walls of said vault, a protective cover for said vault and a groove in the under side of said cover to receive said tongue as a means of keeping said cover properly positioned over said vault and as a means of preventing moisture from entering between said cover and top of the vault.

7. In an individual mausoleum, said mausoleum having a waterproofed vault and cover therefor, an opening as a drain in the floor of said vault and a filter around said opening, the floor of the vault sloping to said opening, and a disinfectant and deodorant around said filter so that moisture in the vault will drain through the disinfectant, deodorant and filter and be discharged from the vault through said opening.

8. In an individual mausoleum, said mausoleum having a vault, said vault having an integral bottom, side and end walls, a sealing tray in the upper portion of said vault and a sealing lid spaced above said sealing tray, said sealing lid being sealed air tight to the walls of the vault, strut bars, said strut bars being positioned on top of said sealing tray and reaching from one wall of the vault to the wall on the opposite side of the vault thereby forming a series of compartments between the sealing tray and sealing lid, openings at the top and between each of

the compartments, and a disinfectant and deodorant in the intermediate compartments, ribs on the under side of said sealing cover, said ribs being positioned between said strut bars, holes in the ends of the sealing tray as a means of permitting a circulation of air from the vault proper through said compartments, said air being deflected downwardly in said compartments by said ribs to contact the disinfectant and deodorant in said compartments and then complete 10 its circuit into the vault proper substantially as described and for the purpose set forth.

9. In an individual mausoleum, a vault, means for the air tight sealing of said vault, a drain in the bottom of said vault, a filter around said 15 drain and a disinfectant around said drain, a sub-floor positioned over said drain and filter and disinfectant as a means of preventing moisture from dripping into said drain and forcing said moisture to flow through said disinfectant 20 and filter.

10. In an individual mausoleum, said mausoleum having a vault whose floor and walls are integral, the upper edges of said walls having an upwardly extending tongue, a cover for said 25 vault, said cover having grooves therein to receive the tongue on the walls of the vault, a reinforced concrete overcoating for said floor and walls and a water proof membrane intermediate said floor and walls and said reinforced concrete 30 overcoating, a water proof sealing material covering the said tongues and upper edges of the vault walls, said sealing material joining said water proof membrane and also forming a water proof joint between said vault walls and the 35 cover for said vault.

BENJAMIN F. KREHBIEL.
